INVENTOR

Robert W Johnson
by E. E. Masson, Attorney.

UNITED STATES PATENT OFFICE.

ROBERT W. JOHNSON, OF NEW BRUNSWICK, NEW JERSEY.

CASE FOR SURGICAL INSTRUMENTS.

SPECIFICATION forming part of Letters Patent No. 543,991, dated August 6, 1895.

Application filed June 7, 1895. Serial No. 551,980. (No model.)

To all whom it may concern.

Be it known that I, ROBERT W. JOHNSON, a citizen of the United States, residing at New Brunswick, in the county of Middlesex, State of New Jersey, have invented certain new and useful Improvements in Cases for Surgical Instruments, of which the following is a specification, reference being had therein to the accompanying drawings.

10 My invention relates to compartment-boxes, and is intended for holding surgical instruments, and particularly bougies or catheters. These instruments are preferably made of a material known as "soft gum," or of textile material coated with said soft gum, and when packed in contact with others of the same material they are liable to become stuck together and thus have their smooth surface roughened, and consequently be spoiled for 15 use, when subjected to the heat of the summer or when put in a warm place in a physician's office or in the drug-stores.

These objects of my invention are to produce in connection with an inclosing box a simple and inexpensive but strong case or tray to hold said surgical instruments without danger of their becoming stuck together, but permitting the distinguishing features of each instrument to be examined without 20 handling it or removing it from the tray. I attain these objects by the construction illustrated in the accompanying drawings, in which—

Figure 1 is a perspective view of a surgical case or tray constructed in accordance with my invention, the front end of two catheters being shown therein. Fig. 2 is a perspective view of a box of suitable size to contain one of the trays. Fig. 3 is a transverse vertical 25 section through one of the trays, its inclosing box, and its cover. Fig. 4 is a perspective view of a portion of the cardboard bottom and partitions used in the construction of the trays.

30 In said drawings, B represents the bottom of the tray. It consists of a rectangular portion of a sheet of cardboard longer than any of the catheters c, or other instrument intended to be placed therein. Said bottom B has on one side another rectangular portion B², preferably integral therewith, but of shorter length, that is wrapped alternately

over and under pieces of metal or of wood, that are preferably rectangular, (but may be cylindrical,) to form therefrom a strip of corrugated paper B³, from which pockets b and b² are obtained.

The bottom B of the tray constitutes the floor of the pockets b, while the inverted arches formed by the corrugated paper B³ constitute the floor of the pockets b². The under side of the floor of the pockets b² is glued or cemented to the upper surface of the bottom B of the tray, and thus retained in proper position upon said bottom B. The bottom B has also a rectangular portion B⁴ projecting from the side opposite the portion B², that is creased and bent at b⁵ to constitute the top B⁵ of the tray, and to the under side of said top the strip of corrugated paper B³ is glued to properly brace the upper portion of the sides of the pockets b and b². The edge of the top B⁵ is creased and bent at b⁶, and the portion B⁶ is glued to the vertical side B⁷, Fig. 4, of the corrugated paper, thus securing together all the sides of the tray. The pockets b and b² are generally kept closed at one end by a strip of strong paper b⁸ glued to the sides of the tray.

After the tray is completed, any desired number of bougies or catheters c are placed in the pockets b and b², and the tray, with its contents, is placed in a box D, preferably of substantial pasteboard, made to fit around the sides of the tray, and of such depth as to receive either one tray alone, as shown by full lines in Fig. 2, or two or more superposed trays, by making the box deeper, as shown by the dotted lines in said figure. The box is closed by means of a cover D² of suitable construction.

Having now fully described my invention, I claim—

1. In combination with a box D, a surgical instrument tray received therein and consisting of a sheet of card-board having its central portion forming the bottom B of said tray longer than said surgical instruments, and its side portions B² and B³ of shorter length, the side B² being corrugated to form the sides of pockets, and the side B³ folded upon the corrugated side B² to complete said pockets, the portions B, B² and B³ being connected together substantially as described.

2. In combination with a box D, a surgical instrument tray received therein, said tray having its bottom longer than said instruments and its sides and top of shorter length, 5 and between said top, bottom and sides a sheet of rigid material corrugated to constitute the sides of pockets, said sheet having its corrugations cemented to the top and bot-

tom of said tray substantially as and for the purpose specified.

In testimony whereof I affix my signature in presence of two witnesses.

ROBERT W. JOHNSON.
